CLAIM

The ornamental design for a hand pruner, as shown and described.

DESCRIPTION

FIG. 1 is a perspective view of a hand pruner showing our new design;

FIG. 2 is a left side elevational view showing the design for the hand pruner of FIG. 1;

FIG. 3 is a right side elevational view showing the design for the hand pruner of FIG. 1;

FIG. 4 is a front elevational view showing the design for the hand pruner of FIG. 1;

FIG. 5 is a rear elevational view showing the design for the hand pruner of FIG. 1;

FIG. 6 is a top elevational view showing the design for the hand pruner of FIG. 1; and,

FIG. 7 is a bottom elevational view showing the design for the hand pruner of FIG. 1.

The broken line showing of portions of the hand pruner is included for illustrative purposes only and forms no part of the claimed design.
